2,166,559 A	7/1939	Richard
2,580,930 A	1/1952	Kost
3,756,737 A	9/1973	Smith
3,932,904 A	1/1976	Nilsson et al.

FIG. 2 is a right elevation view thereof;

FIG. 3 is a left elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines show portions of a drill bit adapter that form no part of the claimed design.
